(57) **CLAIM**

The ornamental design for an electronic device, as shown and described.

DESCRIPTION

FIG. 1 is a perspective view form the front, top and side of a electronic device showing the new design;

FIG. 2 is a perspective view from rear side of the design shown in FIG. 1;

FIG. 3 is a front view of the design shown in FIG. 1;

FIG. 4 is a rear view of the design shown in FIG. 1;

FIG. 5 is a top side view of the design shown in FIG. 1;

FIG. 6 is a bottom side view of the design shown in FIG. 1;

FIG. 7 is a left side view of the design shown in FIG. 1; and,

FIG. 8 is a right side view of the design shown in FIG. 1.

UNITED STATES PATENT AND TRADEMARK OFFICE
CERTIFICATE OF CORRECTION

PATENT NO. : Des. 612,867 S
APPLICATION NO. : 29/329743
DATED : March 30, 2010
INVENTOR(S) : Pascal Ito Morabito

Page 1 of 1

It is certified that error appears in the above-identified patent and that said Letters Patent is hereby corrected as shown below:

Title Page;
In the "(73) Assignee" field on the cover page, the assignee should read as "Deutsche Telekom AG."

In the "Description" section on the cover page, in the sentence which starts "FIG. 1", the word "form" should be replaced with the word "from."

Signed and Sealed this

Twenty-fifth Day of May, 2010

David J. Kappos
Director of the United States Patent and Trademark Office
